UNITED STATES PATENT OFFICE

DONALD STUART KENNEDY, OF LONGPARISH, ENGLAND

TRACTION BELT

Application filed December 3, 1932, Serial No. 645,605, and in Great Britain December 24, 1931.

This invention relates to traction belts of the overall non-skid type intended more particularly for the tires of road vehicle wheels, the shoe members of the belt being connected in series by coupling links or similar linkages. Traction belts of this type are fitted as an overall attachment around two wheels in tandem, and one such traction belt is described in my prior patent Specification No. 10 1,808,416.

The present invention has for its principal object to provide a light, simplified and inexpensive construction of built-up shoe for these traction belts. Another object is to 15 provide a built-up shoe of interchangeable plate elements or metal blanks, which shoe can be enlarged from its leading edge to its trailing edge, by adding further elements. A further object is to provide a simple means 20 arranged within the shoe for taking up stretch in the traction belt or adjusting the length thereof.

My improved shoe is built up of a plurality of plates or strips of metal arranged transversely of the line of travel of the chain and edge-on to the ground, these strips being connected one to another by assembly bolts and nuts with distance pieces mounted on the bolts between the plates or strips. Fore and 25 aft end-coupling members are also mounted on the assembly bolts, and the whole is so arranged that by the selective positioning of the distance pieces on the assembly bolts, the ends of the coupling members can be spaced 30 apart or be brought closer together. Preferably, these distance pieces are cylindrical and the end coupling chain links are bent to L-shape so that at one end these chain links are back to back whilst their other ends diverge in opposite directions and are connected to suitable coupling links. 35

The invention is hereafter described with reference to the accompanying drawing, in which:—

40 Fig. 1 is a front elevation of one form of the built-up shoe showing two plate elements.

Fig. 2 is a sectional side elevation on line 2—2 of fig. 1.

50 Fig. 3 is a plan view of Fig. 2.

Figs. 4 and 5 are views similar to Fig. 2 of another form of the built-up shoe, showing three plate elements.

Fig. 6 is a perspective view of one of the 55 distance pieces or spacing washers.

The shoe comprises a plurality of plate elements *a* of metal and set across the line of travel of the traction belt and edge-on to the ground. These plate elements are made interchangeable so that a shoe of any desired number of these plates *a* can be quickly constructed. The plate elements of each shoe are connected one to another by assembly bolts *b* and nuts *b*¹, said bolts passing through bolt holes *a*¹ in the ends of the plates *a*. Cylindrical distance pieces *c* are also mounted on the bolts *b* and the plates *a* of each shoe are arranged in parallelism. 60

Adjacent shoes in the traction belt are 65 connected together by suitable coupling linkages. For this purpose, two extremal coupling members as links *d*, are also mounted on each bolt *b*. These two links *d* are shown of L-shape with their respective inturned ends *d*¹ *d*² bent back to back, or approximately parallel to one another, whilst their outer ends diverge fore and aft, that is in opposite directions, as clearly 70 shown in Fig. 2. These outer ends are connected to suitable coupling links *e* shown of ordinary oval construction so that each shoe in the belt can be connected fore and aft with adjacent shoes. Any suitable number of links *e* to form the coupling linkages 75

80 may be provided between adjacent shoes. 85

The plate elements or strips *a* are preferably flat and arch-shaped as shown, with the outside curve of the arch removed so that the outer edge *a*² is straight for a considerable portion of its length, with the inner curved portion *a*³ of the arch forming part of the trough for the tire *T*. The straight edge *a*² will prevent lateral rocking of the plate or strip *a* and make better engagement 90 with the ground. The arching *a*³ is with advantage such that a line connecting the bolt holes *a*¹ in the ends through which the assembly bolts *b* are passed, is nearer the center of the road wheel than the inner edge *a*³ 95 100

of the plate or strip a with which the tread of the tire makes contact.

The distance piece c which acts as a spacing washer, is easily slipped upon the securing bolt b and between the plate element a and one of the abutting inturned bends d^1 (see left hand side of Figure 2), or between the facing ends of the two inturned bends d^1 (see right hand side of

Fig. 2). By selectively positioning the distance pieces c upon the bolts b at each side of the built-up shoe, the extremital coupling members d can be spaced apart or be brought closer together.

Adjustment of the length of the coupling linkage is thus effected by changing the position of the distance pieces c between the plates or strips a of the shoe, and these plate elements a of each shoe are always maintained at the same distance apart. Thus the distance piece c may be between the facing ends of the inturned bends d^1 , in which case it separates them so that the outer divergent ends of the links d project fully beyond the strips a , or the distance piece may be between one plate a and the inturned bend d^1 of one link, in which case the outer end of that link does not project so far beyond that plate (the inturned bend of the other link d being directly against the inside of the other plate a and projecting fully). The head of bolt b and nut b^1 hold the plate elements a , distance piece c and inturned bends d^1 firmly clamped together, and after removing the nut b^1 from each bolt b , it is a simple matter to re-assemble the parts with the distance pieces c in another position upon their assembly bolts b .

By this means an adjustment in total length of the traction belt can be made equal to the length of the distance piece c multiplied by the number of shoes a in the belt.

Whilst each built-up shoe need consist of only two transverse plate elements a , I may employ more than two for each shoe, with suitable distance pieces c in between, and preferably in the form of short cylinders or spacing washers mounted upon the assembly bolts b . In this way, the shoe can be enlarged when desired, the increase in the number of plate elements a and distance pieces c providing a shoe which is larger from leading edge to trailing edge. Such an arrangement is illustrated in Figs. 4 and 5 where three plate elements a are employed in each shoe with two distance pieces c on each bolt b . The maximum take-up obtainable in the coupling chain links e will be seen by comparing these Figures 4 and 5. In Fig. 4, the divergent ends of the links d project fully beyond the leading and trailing edges of the outer plates a , the two distance pieces c and the middle plate element a being all interposed between the inturned ends d^1 , whilst in Fig. 5 the outer divergent ends of the links

d are brought closer together and the in-turned ends d^1 are separated only by the thickness of the middle plate element a .

It will thus be understood that shoes of any desired extent from front to rear can be built-up and of these plate elements a , assembly bolts b , distance pieces c and L-shaped links d .

What I claim is:—

1. In a traction belt, a series of built-up shoes, each shoe comprising a plurality of metal plate elements extending transversely of the line of travel of the belt, assembly members holding said plate elements together, a distance piece mounted on each of said assembly members and intermediately of the plate elements, and coupling linkages between the said shoe and adjacent shoes of the belt, each of said coupling linkages being engageable with one of said assembly members in more than one position relatively to the distance piece on that assembly member.

2. In a traction belt, a built-up shoe comprising a plurality of metal plate-elements arranged transversely of the line of travel of the belt and edge-on to the ground, assembly members passing through each said plate-element, distance pieces mounted on said assembly members and between said plate-elements, and coupling linkages extending fore and aft of each shoe, said coupling linkages including extremital links with inturned portions, said inturned portions being also traversed by said assembly members.

3. In a traction belt, a built-up shoe comprising a plurality of interchangeable metal plates extending transversely of the line of travel of the belt, assembly members passing through each said plate, distance pieces mounted on said assembly members and between said plates to hold the plates in parallelism, and coupling linkages secured at their ends to said assembly members in between the said plates.

4. In a traction belt, a built-up shoe comprising a plurality of plate elements arranged transversely of the line of travel of the belt and edge-on to the ground, assembly members passing through each said plate, spacing washers mounted on said assembly members and between said plate elements, and coupling linkages for connecting the shoe with adjacent shoes in the belt, said coupling linkages including L-shaped links which are mounted on said assembly bolts between the plate elements of the shoe.

5. In a traction belt, a built-up shoe comprising a plurality of parallel metal plates arranged across the belt and edge-on to the ground, said plates being bored with bolt holes adjacent to the ends of said plates, assembly bolts passing through said bolt holes, cylindrical distance pieces mounted on said assembly bolts in between said plates, and linkages for coupling the shoe with ad-

ja cent shoes in the belt, each said linkage having an L-shaped extremital link mounted on one of said assembly bolts and in between said parallel metal plates.

5 6. In a traction belt, a shoe comprising a plurality of ground-engaging metal plates arranged transversely of the line of travel of the belt, assembly bolts securing said plates together, links mounted on said assembly bolts and spacing washers also mounted on said bolts, said links and washers being arranged between the said ground-engaging plates of the shoe and being interchangeable in position upon said assembly bolts.

10 7. In a traction belt, a shoe comprising a plurality of ground-engaging plate elements arranged across the belt and edge-on to the ground, said plates having a straight outer edge and a curved inner edge, assembly bolts securing said plate elements together, said bolts passing through the plate elements adjacent to the ends of the said curve, coupling links traversed by said bolts, said coupling links having portions bent to 15 extend beyond one of the said plate elements and spacing washers also traversed by said bolts, said links and washers being arranged between the said ground-engaging plate-elements and being interchangeable in position 20 on said bolts.

25 8. A traction belt of the overall type, comprising a series of built-up shoes coupled together, each said shoe including a plurality of parallel metal plates extending transversely of the line of travel of the belt, assembly bolts connecting said plates together, a forwardly extending coupling link mounted on each of said bolts between said plates, a rearwardly extending coupling link also 30 mounted on each of said bolts between said plates, the forwardly extending link and the rearwardly extending link on each bolt having portions arranged parallel to one another, and spacing washers also mounted on 35 said assembly bolts between said plates.

40 In testimony whereof I have affixed my signature.

DONALD STUART KENNEDY.
